1

My copending United States patent application No. 680,930, filed July 2, 1946, Patent No. 2,582,726, granted January 15, 1952, relates to a mixing circuit arrangement in which the incoming oscillations are supplied in pushpull and the local oscillations in phase coincidence to the input electrodes of two discharge systems; and in which the circuit constituted by the parallel-connected impedances of both halves of the push-pull circuit and the parallel-connected input impedances, jointly with the impedances common to the input circuits of the two systems, is tuned to the frequency of the local oscillations. The expression "push-pull circuit" is to be understood to mean the assembly of impedances interposed between two not directly interconnected input electrodes of the discharge systems, in which are flowing currents having the frequency of the incoming oscillations. The expression "input circuit of a discharge system" is to be understood to mean all the impedances interposed between the input electrodes of a discharge system and in which are circulating currents associated with this system and having the frequency of the local oscillations.

My copending United States patent application aforementioned, describes a form of construction, in which the impedances common to the input circuits, i. e. the impedances by means of which the said circuit (hereinafter called "single phase circuit") is tuned to the frequency of the local oscillations, are interposed between the middle of the push-pull circuit and ground, and between the interconnected cathodes of the discharge systems and ground respectively. Due to this, only one of the two said points (the middle of the push-pull circuit or the junction of the cathodes of the discharge systems) can be grounded. In a particular form of construction, in which the impedances common to the input circuits are distributed with respect to the junctions of the antenna to the push-pull circuit in order that the antenna may be connected in a voltage minimum of the local oscillations, none of these points can be grounded.

The object of the present invention is to provide greater freedom in grounding the junction of the cathodes—generally the junction of two corresponding input electrodes of the discharge systems and/or the middle of the push-pull circuit.

According to the invention this is achieved by tuning the single phase circuit to the frequency of the local oscillations by means of a network interposed between the junction of the two cor-

2

responding input electrodes of the discharge systems and/or the middle of the push-pull circuit on the one hand and the remaining input electrodes and/or the antenna junctions on the other hand.

This permits either the said junction or the middle of the push-pull circuit or both points to be connected at will to a point having a constant potential (ground). On the other hand, it is possible at the same time to connect the antenna in a voltage minimum of the local oscillations and/or to match the antenna conveniently to the discharge systems.

Grounding the said points or any of them yields various advantages. For instance, when the cathodes of the discharge systems are both connected to ground the cathode direct current and the heating current may be supplied to those systems without any difficulty or complication in the construction. In the case of the control grids of the discharge systems being interconnected and the middle of the push-pull circuit disposed between the cathodes being grounded, the two currents may also be supplied in a very simple manner. By making use of a positive feedback for the single-phase circuit, the local oscillations may be produced in the circuit arrangement itself. When this method is employed, and the pair of interconnected input electrodes is grounded, the circuit, in receiving short waves, can be established by means of a cavity resonator. When the middle of the push-pull circuit is grounded, the signals received by the antenna and having a frequency corresponding to the intermediate frequency cannot cause material disturbances.

Preferably the network is completed first followed by tuning the push-pull circuit to the frequency of the incoming oscillations. In some cases, however, the push-pull circuit will be tuned to the frequency of the incoming oscillations, followed by interposition of the impedances by means of which the single-phase circuit is tuned to the frequency of the local oscillations. By providing these impedances the tuning of the push-pull circuit is compromised as a rule. However, this can be reduced to a minimum by giving these impedances a suitable value.

Preferably one or more star-connections are provided whose branches connected to the input electrodes that are not interconnected and to the antenna junctions respectively are made inductive, whereas the other branches are made capacitative.

In a special case, in which the incoming os-

cillations are supplied through a Lecher system to the discharge systems and in which the push-pull circuit is tuned to the frequency of the incoming oscillation, such an impedance can be interposed between the input electrodes which are not connected so as to achieve optimum matching of the antenna to the discharge systems.

As an alternative, magnetically coupled inductances may be included in each half of the 10 push-pull circuit between the antenna junctions and the discharge systems (preferably close to the said junctions).

Figure 1 of the drawing represents a mixing circuit according to my copending patent application heretofore mentioned, in which the incoming oscillations are supplied in push-pull relationship and the local oscillations in phase coincidence to the control grids of two discharge systems 1', 1''; this mixing circuit forms part of a superheterodyne receiver for short waves. The incoming oscillations received by a dipole antenna 2', 2'' are fed to two conductors 3', 3'' forming part of a Lecher system which, by means of a short-circuit bridge 4, is tuned to the frequency of the incoming oscillations. The antenna 2', 2'' is so connected to the Lecher system 3', 3'' as to match the antenna correctly to the mixing tubes. The Lecher system is connected to the control grids R', R'' of the discharge systems 1', 1'', and the cathodes of the discharge systems are interconnected at S. The middle of the short-circuit bridge 4, which is the middle of the push-pull circuit, is represented by P, the junctions of the antenna to the Lecher system being represented by Q', Q''. Advantageously the two triodes 1', 1'' may be housed in one tube and may have a cathode in common.

A resonant circuit tuned to the intermediate frequency and consisting of two inductances 6', 6'' and two condensers 7', 7'' is connected in push-pull arrangement to the anodes of the two triodes. In series with coils 6', 6'' are connected high-frequency chokes 8', 8'', which serve to prevent a transmission of the incoming high-frequency oscillations to the receiver stages next to the mixing stage. The junction of coils 6' and 6'' is connected to ground through a condenser 9, which constitutes practically a short-circuit in regard to intermediate-frequency oscillations, and through a resistance 10 to the positive terminal of a source of anode potential (not represented). Furthermore coils 6' and 6'' are inductively coupled with a second intermediate-frequency circuit which consists of a coil 11 and a condenser 12 and from which the output voltage of the circuit arrangement is taken. The junction of the condensers 7' and 7'' is connected to the cathodes of the two triodes so as to obtain an electric circuit having a low impedance in regard to anode currents having the oscillator frequency.

The middle of the push-pull circuit P is connected to ground through a condenser 13, and the junction of the cathodes 3 is grounded through a variable condenser 14 and an inductance 15 which is coupled with a coil 16 included in the output circuit of a diagrammatically represented local oscillator O. With the aid of the coil 15, the local oscillations are fed to the input circuit of the triode by means of so-called "cathode injection" so that the local oscillations are set up in phase coincidence at the control-grids of the two triodes.

The aforesaid circuit arrangement, as shown

by Fig. 1, exhibits the drawback that the input impedances of the triodes, which are represented by the capacities 5', 5'', particularly in receiving ultra-short waves, have only a small value, due to which the voltage having the oscillator frequency and appearing between the control-grid and the cathode of each of the tubes usually becomes too low. To supply as high as possible a voltage having an oscillator frequency to the control grids of the mixing triodes, my copending patent application heretofore mentioned proposes tuning the circuit constituted by the parallel-connected impedances of both halves of the push-pull circuit and the parallel-connected input impedances of the two discharge systems, jointly with the impedances common to the input circuits of the two systems, to the frequency of the local oscillations.

In the circuit arrangement represented in Fig. 1, this circuit is constituted by the series-connection of the condensers 13, 14, the coil 15, the parallel-connected capacities 5' and 5'' and the parallel connected Lecher lines 3' and 3''. In fact, the voltage set up across the capacities 5' and 5'' and having the oscillator frequency, i. e. the voltage set up between the control grid and cathode of each triode, is a maximum in the case of series-resonance in the said circuit. Hence, this circuit must be tuned to the oscillator-frequency. By tuning, the series-connection of the condenser 13 and the parallel-connected parts of the Lecher line between the points P and Q' and Q'' respectively, as well as the series-connection of the condenser 14, the inductance 15, the parallel-connected input capacities 5' and 5'' and the parallel connected parts of the Lecher line between points R', Q' and R'', Q'' respectively to the oscillator-frequency, the radiation of the local oscillations from the antenna 2', 2'' can be reduced to a minimum. To achieve this the capacity of condensers 13 and 14 may be made variable and these elements may be adjusted in such a manner that the radiation of the local oscillations from the antenna is a minimum, whereas the voltage having the oscillator frequency and being set up between the control-grid and the cathode of each triode is a maximum.

Due to the aforesaid expedients for tuning the single-phase circuit, neither the middle of the push-pull circuit P nor the junction of the cathodes can be grounded. The present invention provides means for grounding at will one or both of these points.

Figs. 2, 3 and 4 of the drawing represent three embodiments of the invention.

The circuit arrangement shown in Fig. 2 substantially corresponds to that represented in Fig. 1, but the condensers 13 and 14, the inductances 15 and 16 and the local oscillator O are missing. Furthermore, an inductance 22 is interposed between the junction of the cathodes S and the junction of the condensers 7' and 7''. Owing to the presence of this coil, through which flows exclusively a current having the frequency of the local oscillations, a positive feedback is obtained with respect to local oscillations. Assuming that the oscillator O were still available, an alternating anode voltage having the oscillator-frequency would be set up, due to the voltage loss through this coil, between the anode and cathode of each triode 1' and 1''. This voltage would lag the alternating control grid voltage by 90°. Consequently, currents having the oscillator-frequency, which are in phase with the

alternating control-grid voltage and which bring about undamping of the single-phase circuit, are flowing through the anode/control-grid capacities denoted by 21' and 21'' in the drawing. In the case under view this undamping is raised to such a degree that the arrangement itself generates oscillations having the oscillator frequency, so that a separate oscillator can be dispensed with.

According to the invention, a network, by means of which the single-phase circuit can be tuned to the frequency of the local oscillations, is interposed between the points P and S on the one hand and the points Q', Q'' and R', R'' on the other hand. One half of this network consists of two equal inductances 17' and 17'', which are placed in series-connection between the points Q' and Q'', a variable condenser 18 connected between the point P and the junction of coils 17' and 17'', and the parts of the Lecher system 3', 3'' located between the point P and the points Q' and Q'' respectively. The other half of the network consists of two equal coils 19' and 19'' connected in series between points R' and R'', a variable condenser 20 placed interposed between the points S and the junction of coils 19' and 19'' and the parts of the Lecher system 3' and 3'' located between the points Q', R' and Q'', R'' respectively.

The capacity of the condenser 18 is now adjusted in such a manner that the part of the single-phase circuit between point P and the points Q' and Q'' respectively is tuned to the frequency of the local oscillations. Since only currents having the frequency of the local oscillations are flowing through the condenser 18, the single-phase circuit can be tuned by means of this condenser without compromising the tuning of the push-pull circuit. Similarly, the part of the single-phase circuit between points S and Q' and Q'' respectively is likewise tuned to the frequency of the local oscillations by adjustment of the condenser 20. Thus not only the whole of the single-phase circuit is in series-resonance with respect to the frequency of the local oscillations, but also the antenna 2', 2'' is connected at a voltage minimum of the local oscillations, so that these oscillations are not radiated to any appreciable extent. By adjustment of the Lecher system 3', 3'', the push-pull circuit can be tuned to the frequency of the incoming oscillations.

When making use of the network set out hereinbefore for tuning the single-phase circuit, both the junction of the cathode S and the middle of the push-pull circuit P can be grounded. This permits the cathode-direct current and the heating current to be fed directly to the point S, whereas in the circuit arrangement shown in Fig. 1 this can take place only through high-frequency chokes. In this case, moreover, the inductance 22 may be realized in the form of a cavity resonator by means of which the frequency of the local oscillations can be stabilized. The junction of the condensers 7' and 7'' is preferably connected to a tapping of this resonator. In the arrangement shown in Fig. 1 this method of stabilization is not advantageous, since in this case the outside of the resonator cannot be grounded with respect to high frequency.

Grounding of the point P yields the advantage that the source of negative grid bias can be connected to this point without any complication. Moreover, the signals in the antenna having a frequency corresponding to the intermediate fre-

quency can no longer cause disturbances in the receiver stages next to the mixing stage. In fact, these signals, which are usually induced in the same phase on both halves of the dipole antenna

5 2', 2'', may cause disturbances if the push-pull circuit is not exactly symmetrical and a considerable impedance in regard to oscillations having the intermediate frequency is available between the antenna junctions and ground. This is 10 avoided, however, by grounding the middle of the push-pull circuit, since in this case the impedance between the antenna junctions Q', Q'' and ground is very low in regard to oscillations having the intermediate frequency, so that even with 15 a slightly asymmetrical push-pull circuit, the disturbances cannot reach to the intermediate-frequency stage.

In some cases the condenser 20 may be omitted. In fact, when tuning the part of the single-phase 20 circuit which is located between the points Q', Q'' and the point S, by means of the Lecher system 3', 3'' first to the frequency of the local oscillations, for instance by a judicious choice of the location of the antenna junctions Q', Q'', and 25 by subsequently tuning the push-pull circuit to the frequency of the incoming oscillations, the correct matching of the antenna to the discharge systems will generally be compromised. This evil 30 can be eliminated by providing an impedance between points R' and R'' and by tuning anew, the push-pull circuit by means of the short-circuit bridge 4; the impedance is so chosen as to achieve optimum matching of the antenna, i. e. a maximum signal-to-noise ratio or a maximum amplification. For instance, when the inductance of 35 the part of the Lecher system between points Q', Q'' and R', R'' has become high as a result of the tuning of the said part of the single-phase circuit to the frequency of the local oscillations, 40 the matching of the antenna and the tuning of the push-pull circuit can be adjusted again to their correct values by interposing a suitable inductance between the points R' and R'' and by tuning at the same time the push-pull circuit by 45 means of the short-circuit bridge to the frequency of the incoming oscillations. If the inductance of the said part of the Lecher system has become too low, a condenser should be substituted for the coil.

50 Fig. 3 represents a circuit arrangement according to the invention, in which the input resonant circuit is provided between the cathodes of the triodes 1' and 1'', the grids being jointly grounded through the inductance coil 15. In this 55 case the positive feedback for the local oscillations is obtained by means of an inductance 23. By giving the inductance of this coil a suitable value the feedback can be made so strong that the circuit arrangement itself generates the local oscillations, so that a distinct local oscillator can be dispensed with. Each anode circuit comprises a coil 24' and 24''; moreover, owing to the presence of these coils, positive feedback is obtained in regard to the incoming oscillations, as 60 a result of which the push-pull circuit is undamped.

The push-pull circuit consists of two series-connected coils 25' and 25'' and a tuning condenser 26, by means of which the push-pull circuit can be tuned to the frequency of the incoming oscillations. The junction P of coils 25' and 25'', which is the middle of the push-pull circuit, is connected directly to ground. The antenna 2', 2'' is inductively coupled with the coils 25' and 25'' through an inductance 27. On the coils

25', 25'' two points Q', Q'' can be indicated which have the same function as the antenna-junctions in the circuit shown in Figs. 1 and 2. These may be considered as points to which the antenna is effectively connected, without making any difference in regard to the remaining part of the circuit. According to the invention a star-connection is provided between these points and the point P, the branches of the star connection being constituted by two equal coils 17' and 17'' and a variable condenser 18.

By means of the condenser 18 the part of the single-phase circuit located between the point P and the points Q' and Q'' respectively can be tuned to the frequency of the local oscillations. The part of the single-phase circuit located between ground and the points Q' and Q'' respectively, reckoned via the point S and the points R' and R'' is likewise tuned to the frequency of the local oscillations by making the inductance 15 connected between point S and ground variable and by adjusting it to the correct value. In this way the whole single-phase circuit is brought into resonance with respect to the frequency of the local oscillations, the antenna 2', 2'' being at the same time connected to a voltage node of these oscillations.

By grounding the point P the cathode direct current can be supplied in a simple manner. In the present case the heating current might be fed through the intermediary of double wound coils 25', 25'' to the cathodes of the triodes. When the push-pull circuit, in using ultra-short waves, is realized in the form of a Lecher-system, the heating current can be fed in a simple manner to the cathodes by making use of a Lecher system in which each conductor consists of two coaxial conductors, one of which serves in any instance for supplying and one for carrying off the heating current.

If desired, the coil 15 may be replaced by a star-connection similar to that used in the arrangement shown in Fig. 2 between points S and R'. In this case two coils 19' and 19'' are connected in series between the two cathodes R' and R'', the junction of these coils being connected through a condenser 20 to the points S. In this way also the point S may be grounded, which yields the advantage that the source of negative grid bias can be connected directly to the point S.

An alternative, the star-connections used in Figs. 2 and 3 may be realized with two capacities and an inductance, in which the capacities are interposed between points Q' and Q'' and between points R' and R'' respectively. However, the star-connections represented in Figs. 2 and 3 permit a much simpler adjustment. Instead of the aforesaid star-connections use may also be made of the equivalent delta-connections. However, these are usually more complicated.

Fig. 4 represents a modification of the left-hand part of the push-pull circuit of the arrangement shown in Fig. 2. In this case, however, the point P is not directly grounded, but through a resistance 28.

In receivers that are tunable over a definite frequency range, it may occur that the part of the single-phase circuit between ground and the points Q' and Q'' respectively is not exactly tuned to the frequency of the local oscillations, so that this part behaves, for instance, as a large capacity. In this case this capacity, jointly with the parallel-connected inductances of the push-pull circuit, in so far as these are located between the point P and the points Q' and Q'' re-

spectively (in the case under view the part of the Lecher system on the left of points Q', Q'') is set in parallel-resonance in regard to the said frequency, which, of course, is very undesirable. To prevent this the left-hand part of the Lecher system may be made aperiodic by connecting it to ground through a resistance 28 having a value corresponding to the surge resistance of the parallel connected Lecher lines 3', 3'' with respect to ground.

The invention applies not only to mixing circuits in which triodes are used, but also to mixing circuits in which use is made of diodes, tetrodes, and so on.

It is not absolutely necessary for the pair of corresponding interconnected input electrodes of the discharge systems to be directly interconnected; but sometimes it may be desirable to interconnect these electrodes, for instance, through a Lecher line or a set of coils.

What I claim is:

1. An electrical circuit arrangement for mixing a first wave and a second wave, comprising the following elements in series circuit arrangement, first and second mixing elements arranged in parallel relationship and each comprising co-operating electrodes in capacitive relationship, means to apply said first wave in phase coincidence to said mixing elements, means including a resonant impedance system having a first point constituting a substantially electrically centered tapping to apply said second wave in push-pull relationship to said mixing elements and means to tune said series circuit to the frequency of said first wave and to provide in said impedance system second and third points at a potential node for said first wave, first and second reactive elements coupled in series between said second and third points, a third reactive element coupled between said electrically centered tapping and the junction of said first and second reactive elements to tune said first and second reactive elements to the frequency of said first wave, and means to apply said second wave to said impedance system.

2. An electrical circuit arrangement for mixing a first wave and a second wave, comprising the following elements in series circuit arrangement, first and second mixing elements arranged in parallel relationship and each comprising co-operating electrodes in capacitive relationship, means to apply said first wave in phase coincidence to said mixing elements, means including a resonant impedance system tuned to the frequency of said second wave and having a first point constituting a substantially electrically centered tapping to apply said second wave in push-pull relationship to said mixing elements and means to tune said series circuit to the frequency of said first wave and to provide in said impedance system second and third points at a potential node for said first wave, first and second reactive elements coupled in series between said second and third points, a third reactive element coupled between said electrically centered tapping and the junction of said first and second reactive elements to tune said first and second reactive elements to the frequency of said first wave, and means to apply said second wave to said impedance system at said points of voltage node of said first wave.

3. An electrical circuit arrangement for mixing a first wave and a second wave, comprising the following elements in series circuit arrangement, first and second mixing elements arranged

in parallel relationship and each comprising co-operating electrodes in capacitive relationship, means to apply said first wave in phase coincidence to said mixing elements, a Lecher system comprising first and second conductors having an open end thereof coupled to said mixing elements in push-pull relationship and having a closed end to tune said Lecher system to the frequency of said second wave and means to tune said series circuit to the frequency of said first wave and to produce on each of said conductors a potential node for said first wave at points on said conductors intermediate to said closed end and said mixing elements, first and second reactive elements coupled in series between said points on said conductors, a third reactive element coupled between said closed end and the junction of said first and second reactive elements to tune said first and second reactive elements to the frequency of said first wave, and means to apply said second wave to said Lecher-system at said points of potential node.

4. An electrical circuit arrangement for mixing a first wave and a second wave, comprising a pair of mixing elements each having cathode, grid and anode electrodes, said electrodes having interelectrode capacities therebetween, a Lecher system comprising first and second conductors having an open end thereof coupled to said grids in push-pull relationship and having a closed end to tune said Lecher system to the frequency of said second wave, means to interconnect said cathodes, an inductive element coupled in regenerative relationship between said cathodes and said anodes to apply said first wave to said cathodes in phase coincidence, a first impedance network intercoupling said control grids and said cathodes and having a variable reactive element to produce on each of said conductors a potential node for said first wave at points intermediate to said closed end and said grids, a second impedance network intercoupling said points of potential node and said closed end and having a second variable reactive element to tune said second impedance network to the frequency of said first wave, said Lecher system, said first impedance network and said second impedance network constituting a series circuit tuned to the frequency of said first wave, and means to apply said second wave to said Lecher-system at said points of potential node.

5. An electrical circuit arrangement for mixing a first wave and a second wave, comprising a pair of mixing elements each having cathode, grid and anode electrodes, said electrodes having interelectrode capacities therebetween, a Lecher system comprising first and second conductors having an open end thereof coupled to said grids in push-pull relationship and having a closed end to tune said Lecher system to the frequency of said second wave, means to interconnect said cathodes, a first inductive element coupled in regenerative relationship between said cathodes and said anodes to apply said first wave to said cathodes in phase coincidence, an impedance network including said grid-cathode interelectrode capacities intercoupling said control grids and said cathodes and having a variable capacitive element to produce on each of said conductors a potential node for said first wave at points intermediate to said closed end and said grids, second and third inductive elements coupled in series between said points of potential node, a second variable capacitive element coupled between the junction of said second and third in-

ductive elements and said closed end to tune said second and third inductive elements to the frequency of said first wave, said Lecher system, said impedance network, said second and third inductive elements and said second variable capacitive element constituting two series circuits tuned to the frequency of said first wave, and means to apply said second wave to said Lecher-system at said points of potential node.

6. An electrical circuit arrangement for mixing a first wave and a second wave, comprising a pair of mixing elements each having cathode, grid and anode electrodes, said electrodes having interelectrode capacities therebetween, an input network tuned to the frequency of said second wave and coupled to said cathodes in push-pull relationship, said input network including an inductor having three taps, one of said taps constituting a substantially electrically centered tapping of said input network, means to couple said centered tapping to ground potential, means to interconnect said grids, a first reactive element coupled between said grids and ground potential, said first reactive element, said grid-cathode interelectrode capacities and said input network constituting a pair of series circuits each tuned to the frequency of said first wave, a second reactive element coupled in regenerative relationship between said grids and said anodes to apply said first wave to said grids in phase coincidence, means to produce potential nodes for the frequency of said first wave at the other taps of said inductor comprising an impedance network tuned to the frequency of said first wave and intercoupling the taps on said inductor, and means to apply said second wave to said inductor.

7. An electrical circuit arrangement for mixing a first wave and a second wave, comprising a pair of mixing elements each having cathode, grid and anode electrodes, said electrodes having interelectrode capacities therebetween, an input network tuned to the frequency of said second wave and coupled to said cathodes in push-pull relationship, said input network including an inductor having three taps, one of said taps constituting a substantially electrically centered tapping of said input network, means to couple said centered tapping to ground potential, means to interconnect said grids, a first inductive element coupled between said grids and ground potential, said first reactive element, said grid-cathode interelectrode capacities and said input network constituting a pair of series circuits each tuned to the frequency of said first wave, a second inductive element coupled in regenerative relationship between said grids and said anodes to apply said first wave to said grids in phase coincidence, means to produce potential nodes for the frequency of said first wave at the other taps of said inductor comprising third and fourth inductive elements coupled in series between the other taps of said inductor, a variable capacitive element coupled between the junction of said third and fourth inductive elements and said centered tapping to tune said third and fourth inductive elements to the frequency of said first wave, and means to apply said second wave to said inductor.

8. An electrical circuit arrangement for mixing a first wave and a second wave, comprising the following elements in series circuit arrangement, first and second mixing elements arranged in parallel relationship and each comprising co-operating electrodes in capacitive relationship, means to apply said first wave in phase coinci-

dence to said mixing elements, means including a resonant impedance system having a first point constituting a substantially electrically centered tapping to apply said second wave in push-pull relationship to said mixing element, a resistive element coupled between said tapping and ground potential and means to tune said series circuit to the frequency of said first wave and to provide in said impedance system second and third points at a potential node for said first wave, first and second reactive elements coupled in series between said second and third points, a third reactive element coupled through said resistance element between said electrical center and the junction of said first and second reactive elements to tune said first and second reactive elements to the frequency of said first wave, and means to apply said second wave to said impedance system.

9. An electrical circuit arrangement for mixing a first wave and a second wave, comprising the following elements in series circuit arrangement, first and second mixing elements arranged in parallel relationship and each comprising cooperating electrodes in capacitive relationship, means to apply said first wave in phase coincidence to said mixing elements, a Lecher system comprising first and second conductors having an open end thereof coupled to said mixing elements in push-pull relationship and having a closed end to tune said Lecher system to the frequency of said second wave, a resistive element coupled between ground potential and said closed
